UNITED STATES PATENT OFFICE.

JULES ROMAIN MARTINET, OF GRENOBLE, FRANCE, ASSIGNOR TO SOCIÉTÉ V. PERRIN & CIE., OF GRENOBLE, ISERE, FRANCE.

MACHINE FOR DYEING HIDES.

Application filed November 27, 1923. Serial No. 677,261.

To all whom it may concern:

Be it known that I, JULES ROMAIN MARTINET, of Chemin Moyrand, Grenoble, Isere, France, a citizen of the French Republic, 5 have invented Machines for Dyeing Hides, of which the following is a full, clear, and exact description.

This invention relates to a machine allowing to obtain the dyeing of hides by 10 means of brushes, sponges, etc., and is essentially constituted by a horizontal table so arranged as to receive through a suitable mechanism an intermittent rotary angular movement about a vertical axis and composed of a number of sectors which, adapted 15 to each support a hide to be dyed come, during the rotation of the table, successively opposite standing operators placed around the said table and each specialized in an 20 operation of the dyeing.

In its preferred form of construction, the table is driven by a piston receiving, in a cylinder, a reciprocating movement under 25 the action of a driving fluid, such that steam or compressed air alternately admitted on one and the other face of the piston by a rotary distributor; the rod of this piston forms a rack constantly in gear with a toothed segment rigid with a ring or crown 30 carrying pawls so arranged as to come in engagement with the notches of a crown rigid with the table and to actuate the latter, during the displacement of the piston in a direction, these pawls disengaging from the 35 said notches, upon displacement of the piston in the opposite direction; this piston thus brings back to its starting position the pawl-carrying ring, but not the table which remains stationary until the following displacement of the piston for permitting the 40 operators to effect their work on the hide which has been brought before them.

In order that the invention may be clearly understood, a form of construction of the 45 dyeing machine forming the subject-matter of the said invention will be described hereafter with reference to the accompanying drawing in which:

Fig. 1 is a longitudinal vertical section of 50 the machine according to line A—A of Fig. 2.

Fig. 2 is a plan view.

Fig. 3 is a horizontal section made according 55 to line B—B of Fig. 1.

Fig. 4 is a partial section, on an enlarged 55 scale, of a detail of construction of the table.

Fig. 5 is a section of the driving device and of its distributing member.

As illustrated in the accompanying drawing, the improved dyeing machine essentially comprises a horizontal table composed of a number of sectors 1 bolted together and screwed on a crown 2 which receives an intermittent angular rotary movement, as will be explained hereafter, with interposition of a bronze friction crown 3, on another 4 secured to the cement foundation work 5.

The sectors 1 are each provided with a recess or housing in which is suitably arranged a glass plate 6 adapted to serve as 70 support for the hides to be dyed and resting in wooden cross bars inserted at their ends in the ribs provided in the said sectors.

The table thus constituted intermittently receives about the central work 5 made of 75 cement, an angular rotary movement of predetermined amplitude in order that the various sectors 1 with the hide carried by each of them may be successively brought opposite standing operators placed around the table, 80 and corresponding in number to the number of sectors of the latter, each operator being specialized in an operation or phase of the dyeing process.

This intermittent angular rotary movement is transmitted to the table by a driving piston 7 mounted in a cylinder 8 and the rod 9 of which is terminated by a rack 10 constantly gearing with a toothed segment 11 rigid with a crown or ring 12 in which 90 are mounted pawls 13 adopted to produce the intermittent actuation of the crown or ring 2 carrying the sectors 1 and presenting notches 14 in which fit the actuating pawls 13.

The driving fluid used for actuating the piston 7 can be steam or compressed air admitted through the pipe 15 in the shell 16 of a distributor, the plug 17 of which, controlled by a small electric motor 18 acting through the medium of suitable speed reducing devices, alternately admits the driving fluid on one or the other face of the said piston 7, thus resulting in the alternating displacement of the latter in its cylinder 8.

During the forward movement of this piston, the rack 10 actuates, through the member 12 and the pawls 13, the crown 2 and the

table proper which, rigid with the latter, rotates through a fraction of a revolution in the direction of the arrow X (Fig. 3).

When the piston has arrived to the end of its stroke, the table is braked by means of a shoe 19 adjustably mounted on the rack 10.

The distributor 17, which rotates with a continuous movement, then sends the driving fluid on the opposite face of the piston 7 which moves backward by driving the rack 10 and member 12 in reverse direction to the arrow X, but not the table which remains stationary until, through the rotation of the distributor, the driving fluid is again admitted on the other face of the piston.

The table rotating as just described, is used in the following manner:

A hide is placed by hand by a first operator on one of the glass plates of the table; 20 after a determined angular rotation of the said table, this hide is presented opposite a second operator who, during the period of stoppage of the table, subjects the hide to a certain operation of the dyeing process; 25 whilst the first operator places a new hide on the plate glass which comes in front of him; after a second angular rotation of the table, the first hide comes opposite a third operator who effects another operation of 30 the dyeing process, whilst the second operator subjects the following hide to the first series of dyeing operations and the first operator places a third hide on the next plate glass coming in front of him, and so on, 35 each of the hides being successively brought opposite operators each specialized in an operation of the dyeing process (placing in po-

sition of the hides, mordanting, application of the dyeing solution, rinsing, removal of the hides, etc.).

It will be understood from the foregoing that the above described machine allows the dyeing by hand by means of brushes, sponges, etc., that it presents the very important advantage of obtaining the desired 45 regularity and finish and to increase the production and the amount of work done by the operators by specializing each of them in a determined operation of the dyeing process.

The above constructional arrangements are 50 of course, given by way of example only; the forms, materials and dimensions of the various constituent parts as well as the number of sectors constituting the table may be varied without departing thereby from the 55 principle of the invention.

Claim—

A machine for dyeing hides by hand comprising a horizontal table composed of a number of sectors each adapted to support a hide to be dyed, a crown fixed to the table and having concentrically arranged notches therein, a ring cooperating with the said crown, pawls mounted on this ring to engage the notches in said crown, a toothed segment 60 on the said ring, a reciprocating rack for engaging and operating the said segment, and fluid pressure means including a distributing valve for operating the rack to impart a step-by-step movement to the table. 65

The foregoing specification of my "machine for dyeing hides," signed by me this 7th day of November 1923.

JULES ROMAIN MARTINET.
